HAIR WAVING MACHINE OR SIMILAR DEVICE

Filed Feb. 27, 1933

INVENTOR:
OLE HIBNERKline, Hudon & Klet
ATTORNEYS

UNITED STATES PATENT OFFICE

OLE HIBNER, OF CLEVELAND, OHIO

DESIGN FOR A HAIR WAVING MACHINE OR SIMILAR DEVICE

Application filed February 27, 1933. Serial No. 47,331. Term of patent 7 years.

To all whom it may concern:

Be it known that I, OLE HIBNER, a citizen of the United States, residing at Cleveland, in the county of Cuyahoga and State of Ohio, have invented a new, original, and ornamental Design for Hair Waving Machines or Similar Devices, of which the following is a specification, reference being had to the accompanying drawing, forming a part thereof, in which

Fig. 1 is a perspective view of a hair waving machine or similar device, and

Fig. 2 is an elevation thereof.

The design comprises a support having a multi-sided base and top with angular de-

signs thereon. This base supports a substantially vertical post upon which there is secured a multi-sided container, adapted to contain functional apparatus, certain of the sides of the container being provided with angular designs. Upon the post above the container is mounted an arm, angular in design, serving as a support for electric conductors.

I claim:

The ornamental design for a hair waving machine or similar device as shown and described.

OLE HIBNER.
